[57] **CLAIM**

The ornamental design for a label box display case, as shown and described.

DESCRIPTION

FIG. 1 is a front perspective view of a label box display case showing my new design;

FIG. 2 is a rear perspective view thereof;

FIG. 3 is a front elevational view thereof;

FIG. 4 is a rear elevational view thereof;

FIG. 5 is a right side elevational view thereof; and

FIG. 6 is a left side elevational view taken along lines 6—6 of FIG. 3.

The bottom is flat and unornamented.
